UNITED STATES PATENT OFFICE.

ATANAS PETER DULGEROFF, OF GRANITE CITY, ILLINOIS.

COMBINATION IRONING-BOARD AND STEP-LADDER.

1,117,645.

Specification of Letters Patent. Patented Nov. 17, 1914.

Application filed April 27, 1914. Serial No. 834,815.

To all whom it may concern:

Be it known that I, ATANAS PETER DULGEROFF, a citizen of Bulgaria, residing at Granite City, in the county of Madison and 5 State of Illinois, have invented certain new and useful Improvements in Combination Ironing-Boards and Step-Ladders, of which the following is a specification, reference being had to the accompanying drawings.

10 This invention relates to new and useful improvements in combined ironing boards and step ladders, and an object thereof is the provision of a device of this character which may be quickly set up for use either 15 as an ironing board or as a step ladder.

Another object of this invention is the provision of a device of this character in which the ironing board and step ladder are pivotally connected together, the device including improved means for supporting either the board or ladder in a position for use.

A still further object of this invention is the provision of a combined step ladder and 25 ironing board, in which means are provided for locking the device either in a position for use as a step ladder or as an ironing board.

With these and other objects in view, my 30 invention consists in the novel construction, combination, and arrangement of parts to be hereinafter more fully described, claimed, and illustrated in the accompanying drawing, in which,

35 Figure 1 is a side elevation of my device in set up position for use as a step ladder; Fig. 2 is a side elevation of the device set up in position for use as an ironing board; Fig. 3 is a top plan view thereof in folded 40 position; Fig. 4 is a sectional view on the line 4—4 of Fig. 3; and Fig. 5 is a sectional view on the line 5—5 of Fig. 2.

Referring more particularly to the drawing, the numeral 1 designates an ironing 45 board of the usual construction which is tapered from its inner end to its outer end, the inner end of the board having a pair of diverging slots 2 formed therein. Secured to the inner face of the board 1 is a plate 3. 50 the plate extending transversely of the board and being formed on its opposite ends with trunnions 4 for engagement in the side bars 5 of a ladder 6, whereby the ladder is pivotally connected to the board. The ladder 55 comprises the usual steps 7 and the top shelf 8, the plate 3 projecting outwardly beyond

the outer edges of the side bars of the ladder and forming the upper step thereof. Pivots 50 connected adjacent its inner end to each of the side bars of the ladder, is a supporting leg 9, the legs being connected at their outer ends by a cross bar 10. The side bars 5 of the ladder extend the entire length of the board 1, and the slots 2 in the board extend from the inner end thereof to 55 a point adjacent the plate 3 so that the inner ends of the bars 5 may project upwardly through the slots 2 when it is desired to use the device as an ironing board, as clearly shown in Fig. 2 of the drawings. The opposite ends of the projecting portion of the plate 3 extend outwardly from the opposite sides of the ladder to form stops 11.

When the device is used as an ironing board, the board 1 is disposed in a horizontal position and the outer end of the ladder is swung downwardly to engage the floor below the outer end of the board, and the supporting legs 9 are also swung downwardly to engage the floor under the inner end of 60 the board, the movement of the legs being limited by their engagement with the stops 11 of the plate 3. With the lower or outer end of the ladder engaged with the floor, the upper ends of the side bars thereof project through the slots 2 so that the upper ends thereof are disposed above the inner end of the board 1, and formed in the inner edge of each of the side bars of the ladder adjacent its upper extremity, is an angular 65 recess 12 which forms a seat for the locking bar 13. The locking bar 13 is pivotally connected at one end to the upper face of the board 1 to one side of the ladder, and connected to the opposite side of the board is a keeper plate 14, so that when the locking bar 70 is swung inwardly so that the free end thereof is engaged with its keeper plate, the body portion of the bar engages in the seats 12 provided in the edges of the side bars of the 75 ladder to prevent the upper ends of the side bars from moving downwardly which will collapse the device. It will be seen that the engagement of the upper ends of the portions of the side bars of the ladder above the 80 board with the locking bar maintains the board in a horizontal position and prevents the outer end thereof from moving downwardly, the upper ends of the supporting legs 9 also engaging the under face of the 85 board forwardly of its pivotal point to further brace the same against downward move-

ment. Upward swinging of the outer end of the board is prevented by reason of the engagement of the stops 11 with the inner edges of the supporting legs 9 and when the 5 various parts of the device are in this position and locked by the locking member 13, it will be seen that an ironing board is provided which is supported rigidly in a horizontal plane. If desired, the locking bar 13 10 may be enlarged intermediate of its ends as at 15, to carry a plate of asbestos 16 or other similar non-conducting material upon which the pressing iron (not shown) which is used in connection with the ironing board, may 15 be supported so as not to burn the board.

When it is desired to use the device as an ordinary step ladder, the inner end of the board and the upper ends of the side bars of the ladder are swung upwardly, the lower 20 extremities of the side bars forming fulcrum points until the free edge of the ironing board engages the floor and, in this position, the ironing board extends vertically, and the ladder is inclined from its 25 lower end to its upper end, the ladder and board being held in their respective positions by the locking bar 13. When the device is used as a step ladder, the legs 9 are 30 swung downwardly, the connecting member 10 of the legs engaging the edges of the side bars of the ladder below one of the steps thereof as shown in Fig. 1 of the drawings, so that the legs are disposed in the same longitudinal plane as the side bars, out of 35 the way of the person using the step ladder. It will be seen that spreading of the board and the ladder in this position is prevented by the engagement of the edges of the side bars of the ladder with the inner walls of 40 the slots 2, and closing of these parts is prevented by the engagement of the locking bar 13 in the seats 12 in the side bars.

When the device is not desired for use, the same may be folded into compact form by merely swinging the free end of the locking bar upwardly on its pivot, so as to remove the bar from engagement in the recesses 12 in the side bars of the ladder, whereupon the inner edges of the side bars 45 may be moved against the inner face of the board, so that the various parts of the device are compactly folded together. The edges of the side bars of the ladder opposite the recesses 12 formed therein, have secured thereto laterally extending loops 17, which project through the slots 2 in the board when the device is in folded position, so that the locking bar may be swung inwardly to cross the slots 2, and engage the 50 outermost portions of the loops 17 which are disposed flush with the outer face of the ironing board, thereby locking the various parts of the device in folded position. 55

From the foregoing description, taken in connection with the accompanying draw-
65

ings, it will be seen that I have provided a combined ironing board and step ladder, in which the device may be readily set up in position for use either as a step ladder or as an ironing board, the step ladder and ironing board being in the same relative positions when the device is used in either manner, it being merely necessary to swing the device upwardly, using the lower extremities of the side bars of the ladder as fulcrums when it is desired to change the device from an ironing board to a step ladder, or to swing the upper end of the device downwardly on the lower ends of the side bars of the ladder when it is desired to change the device from a ladder to an ironing board, the legs 9 supporting the ironing board in a horizontal position. It will also be readily seen that the same locking means locks the ironing board and step ladder in their open positions, and in their folded positions so that the device is rigidly locked in any of its positions.

Having thus fully described my invention, what I desire to claim and secure by Letters Patent, is:—

1. The combination with a board having slots formed therein extending inwardly from the inner end of the board, of a step ladder having its side bars pivotally connected to the board, the inner ends of said side bars being adapted for engagement through the slots in said board, and means carried by the board for engagement between the same and the edges of the projecting portions of the bars, to maintain the inner ends of said bars within the slots. 95 100

2. The combination with a board having a transversely extending plate connected thereto adjacent its inner end, the board having slots formed therein extending from the inner end of the board to points adjacent said plate, a step ladder having its side bars pivotally connected to the opposite ends of said plate, the inner ends of said side bars being adapted for engagement through the slots in said board, the projecting portions of said bars having angular recesses formed in one edge, and a locking plate pivotally connected to the board for engagement in the recesses in said side bars to hold the same within the slots in said board.

3. The combination with a board having a transversely extending plate connected thereto adjacent its inner end, the board having slots formed therein extending from the inner end of the board to points adjacent said plate, a step ladder having its side bars pivotally connected to the opposite ends of said plate, the outer end of said plate being enlarged to project beyond the outer faces of said side bars, the inner ends of said side bars being adapted for engagement through the slots in said board, means for

5 maintaining the inner ends of said side bars within said slots, and supporting legs pivotally connected to the outer faces of said side bars adjacent said plate, said supporting legs being adapted for engagement with the projecting portions of said plate when in their extended position.

4. The combination with a board having slots formed therein extending inwardly 10 from one end of the board, a step ladder having its side bars pivotally connected to the board, the inner ends of said side bars being adapted to project through the slots in the board when the step ladder is in extended position, means carried by the board 15

for engagement between the same and the edges of the projecting portions of the side bars to hold the step ladder in extended position, projections formed upon the inner edges of said side bars to extend through 20 the slots when said step ladder is in folded position, the first mentioned means being adapted to engage said projections to hold the step ladder in folded position.

In testimony whereof I hereunto affix my 25 signature in the presence of two witnesses.

ATANAS PETER DULGEROFF.
